Primary Examiner — Patricia A Palasik*(74) Attorney, Agent, or Firm* — Andrew F. Young, ESQ.;
NOLTE LACKENBACH SIEGEL(57) **CLAIM**

The ornamental design for a robot, as shown and described.

DESCRIPTION

FIG. 1 is a left, front, top perspective view of a robot, showing my new design.

FIG. 2 is a right, front, top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dash-dot-dash lines in the figures mark the claim boundaries beyond which no claim is made. The portions shown in dash-dot lines represent unclaimed portions of the robot that form no part of the claimed design.

1 Claim, 6 Drawing Sheets(56)
